MINIATURE SELF-PROPELLED AIRPLANE

William R. Padgett, Pasadena, Tex.

Application February 20, 1945, Serial No. 578,927

6 Claims. (Cl. 46—77)

1

This invention relates to miniature self-propelled airplanes.

An object of the invention is to provide an airplane of the control line type whose rudder will normally be maintained, by a control line, in position to keep the craft in its outer path, or course, in flight, while the control line is taut; with means for automatically moving the rudder outwardly, should the control line become slack, as in the event the craft should be forced inwardly off its normal path by a side wind, so that the craft will be guided, by the rudder, outwardly into its former, or normal, course.

Another object of the invention is to provide means for maintaining the elevators in position to keep the craft at a selected elevation, in flight, with an elevator control line and means connecting said line to the elevators whereby the position of the elevators and the elevation of the craft may be controlled and varied.

A further object of the invention is to provide means for controlling an aileron of one of the wings, through one or both of the control lines, whereby the craft may be laterally stabilized.

The invention also embodies a novel type of grip, or handle, whereby the control lines may be manipulated.

With the above and other objects in view this invention has particular relation to certain novel features of construction, operation and arrangement of parts an example of which is given in this specification and illustrated in the accompanying drawings, wherein:

Figure 1 shows a perspective view of the aircraft, embodying the invention and partly broken away.

Figure 2 shows an outer end view of one of the wings, or planes, showing the aileron control.

Figure 3 shows a side view of the grip, or handle.

Figure 4 shows a fragmentary, horizontal, sectional view.

Figure 5 shows a fragmentary, vertical, sectional view.

Figure 6 shows a fragmentary, bottom view, partly in section, and

Figure 7 shows a fragmentary, plan view of one of the wings, or planes, partly in section.

Referring now more particularly to the drawings the numeral 1 designates the fuselage as a whole at the forward end of which is the motor driven propeller 2.

Fixed to the fuselage are the laterally extended wings, or planes, 3, provided with ailerons one of which is hinged to move on the hinges 4.

The rear end of the fuselage has the vertical

2

rudder 5 pivoted to move on a vertical axis and also has the elevators 6, pivoted to move on a horizontal axis.

Within the fuselage there is a horizontal plate 7, forming a supporting frame. Above the frame there is a bell crank formed with the cross-head 8 and the lever-arm 9 and beneath the frame there is a bell crank formed with the cross-head 10 and the lever-arm 11. These bell cranks are mounted to rotate on a common pivot 12 and are held spaced from the frame 7 by the upper and lower washers 13 and 14.

Connected to the elevators there is a depending horn 15 and a rigid link 16 is pivoted, at its forward end, to one end of the cross-head 8 and, at its other end, to the lower end of said horn.

One end of a pull spring 17 is connected to the other end of the cross-head and its other end is connected to the post 18 upstanding from the frame.

There are spaced stops 19 and 20 on the frame 7 the former of which extends above and beneath the frame. The range of movement of the arm 9 is limited by these stops.

25 The rudder 5 has a laterally extended horn 21 and a rigid link 22 is pivoted, at one end, to this horn and, at its other end to one end of the cross-head 10. One end of a pull spring 23 is connected to the other end of the horn 10 and the other end of said spring 23 is connected to the post 24 which depends from the frame 7.

There is a stop 25 which depends from the frame 7 and the range of movement of the arm 11 is limited by the stops 19, 25 between which it works.

25 There are the flexible control lines 26, 27 which are connected, at one end, to the free ends of the respective arms 9 and 11. At their other ends the line 26 is connected to the upper end 40 of the hand grip 28 and the line 27 is connected to the middle of said grip, as shown in Figures 1 and 3.

In flight the craft will follow a substantially circular course about the operator on the ground 45 by whom the grip 28 is held. The centrifugal force of the craft will hold the line 27 taut with the spring 23 under tension and with the rudder in intermediate, or neutral, position. Should the craft encounter a side current which forces it inwardly, with respect to the circle of flight, the control line 27 will, at once, become slack and the spring 23 will act, through the cross-head 19 and link 22 to move the rudder outwardly, with respect to said circle, thus causing the craft to 50 resume its original course.

While the craft is in flight the pull on the line 26 will normally balance the pull of the spring 17 and maintain the elevators 6 in horizontal position so as to keep the craft in a level course. Should the craft tend to descend the pull on the line 26 may be increased, by suitable manipulation of the grip 28, and this will actuate the head 8 and link 16 to raise the elevators and guide the craft upwardly; on the other hand should the craft climb the line 26 may be released and thereupon the spring 17 will actuate the head 8 and link 16 and the elevators will be lowered which will cause the craft to descend. The elevation of the craft may, therefore, be controlled by manipulating the line 26.

In order to maintain the craft stabilized laterally the aileron 29 is hinged and a forwardly extended, rigid arm 30 is rigidly secured to the forward edge thereof and extends above the corresponding wing 3. The free end of this arm has the upper and lower eyes 31 and 32 through which the respective lines 26 and 27 pass as shown in Figure 1. The arm 30 works through a vertical guide 33, upstanding from the corresponding wing, as shown in Figures 1 and 2. Should the craft bank toward the operator the lines 26, 27 will remain taut and will cause a corresponding relative upward movement of the arm 30 and downward movement of the aileron 29 which will tend to stabilize the craft; on the other hand should the craft bank in the opposite direction the aileron 29 will be elevated by the arm 30 and the craft stabilized.

On the wing opposite the aileron 29 there is also an aileron 34. This aileron is attached to the wing by means of metal plates 35, one end of each plate being inserted into the wing and the other ends thereof into the aileron 34. These plates are of bendable material but when bent they will remain bent so that the aileron 34 may be adjusted up or down to obtain the best results and will remain in that position until re-adjusted.

Thus the forward direction, the elevation and the lateral stability of the craft is at all times under the control of the operator.

What I claim is:

1. In a miniature, self propelled, airplane having a fuselage, laterally extended wings on the fuselage one of which is provided with an aileron which is hinged thereto, a control line attached at one end to the airplane and whose other end is adapted to be held by an operator on the ground and an arm rigidly connected to the aileron operatively connecting the aileron with the control line whereby the aileron will be moved downwardly as the wing is lowered and moved upwardly as the wing is elevated.

2. In a miniature, self propelled, aircraft having a fuselage, laterally extended wings on the fuselage, an aileron hinged on one of the wings, a rigid arm fixed to the aileron and whose free end is turned horizontally and formed with an

eye and a control line connected, at one end, to the craft and passing through said eye and whose other end is adapted to be held by an operator on the ground.

3. In a miniature, self propelled, aircraft having a fuselage, laterally extended wings, or planes and a rudder pivoted to move on a vertical axis; a cross-head pivotally mounted on the fuselage to move on a vertical axis, a link connected to the cross-head and to the rudder, a yieldable member connected to the cross-head and effective to normally hold the rudder in one position and a control line connected to the cross-head through which the rudder may be held in another position when the craft is in flight.

4. In a miniature, self propelled, aircraft having a fuselage, lateral wings, or planes, thereon, a rudder mounted to pivot on a vertical axis and an elevator mounted to pivot on a horizontal axis; cross-heads pivoted on the fuselage, rigid links connecting one cross-head with the rudder and the other cross-head with the elevator, control lines connected to the cross-heads through which the rudder and elevator may be moved to selected positions, yieldable members connected to the cross-heads effective to move the rudder and elevator to other positions, when the control lines are slack.

5. In a miniature, self propelled, aircraft having a fuselage, lateral wings, or planes, thereon, a rudder mounted to pivot on a vertical axis and an elevator mounted to pivot on a horizontal axis; cross-heads pivoted on the fuselage, links connecting one cross-head with the rudder and the other cross-head with the elevator, control lines connected to the cross-heads through which the rudder and elevator may be moved to selected positions, yieldable members connected to the cross-heads effective to move the rudder and elevator to other positions, when the control lines are slack and stops on the fuselage for limiting the range of movement of the cross-heads and thereby limiting the movement of the rudder and elevator.

6. In a miniature, self propelled, aircraft having a fuselage, lateral wings thereon, a rudder mounted to pivot on a vertical axis and an elevator mounted to pivot on a horizontal axis; cross-heads mounted to move on a common pivot on the fuselage and having extended arms, links connecting one cross-head with the rudder and the other cross-head with the elevator, control lines connected to the arms through which the rudder and elevator may be moved to selected positions, yieldable members connected to the cross-heads effective to move the rudder and the elevator to other positions when the control lines are slack and means for limiting the range of movement of the cross-heads and thereby limiting the movement of the rudder and elevator.

WILLIAM R. PADGETT.
